UNITED STATES PATENT OFFICE.

ARTHUR WALTER, OF NAPLES, ITALY.

APPARATUS FOR PRODUCING SUBLIMED SULFUR.

No. 873,812.

Specification of Letters Patent.

Patented Dec. 17, 1907.

Application filed October 16, 1905. Serial No. 282,916.

To all whom it may concern:

Be it known that I, ARTHUR WALTER, a citizen of the United States, resident of Naples, Italy, have invented certain new and useful Improvements in Apparatus for Producing Sublimed Sulfur, of which the following is a specification.

My invention relates to apparatus for continuously producing sublimed sulfur and has 10 for its object to produce sublimed sulfur of extreme and uniform fineness in an economical manner and with absolute safety against fire or explosion.

My invention will be described in detail 15 hereinafter, and the features of novelty will be pointed out in the appended claims.

Reference is to be had to accompanying drawings in which

Figure 1 is a side elevation, with parts in 20 section, of my improved apparatus; Fig. 2 is a plan view of same; Fig. 3 is a detail section of the retort and adjacent parts.

A represents a retort preferably made of cast iron and located in a suitable furnace B. 25 At one end this retort is provided with a door C to permit cleaning. A pipe D connects said retort A with a boiler E in which the raw sulfur is heated and melted and then is to enter retort A. A pipe A' connects 30 said retort with a tube F which has one end connected by means of a pipe F', with a blower G. The other end of the tube F is connected through the medium of a pipe F² with a metallic cooling chamber H. A pipe 35 or tube H' affords communication between the cooling chamber H and a collector I, which collector I is in turn connected with the suction port of the blower G by means of pipe J, J', J² and J³. The cooling chamber 40 H and the collector I may be of any suitable construction. In Fig. 3 I have shown an injector K of any approved construction located in the tube F for the purpose of increasing the draft.

45 In operation the raw sulfur is first melted in the boiler E and then introduced by the pipe D into the retort A. A strong current of air or better still inert gas is driven by the blower G through the pipe F', tube F and 50 pipe F² into the cooling chamber H. This current tends to produce a vacuum in the retort A thus causing a rapid sublimation of the sulfur in said retort.

The vapors of sulfur in the retort are carried 55 by the aforesaid current of inert gas through the connection A' to the tube F and

through said tube F and pipe F² into the cooling chamber H, in which chamber said sulfur vapors become condensed and are thus transformed into an extremely fine powder 60 of sulfur. After this condensation has taken place in the cooling chamber the current drives the sublimed sulfur through the pipe H' into the collector I. The pipe H' has a downward, enlarged outlet opening a which 65 under the action of the current causes the powdered sulfur to spread out horizontally on the bottom of the collector (instead of rising) and to deposit itself in the bottom of the collector, which may be furnished with 70 sack or bag holes, b, b, so that the powdered sulfur may be filled directly into such sacks or bags.

The inert gas at the top of the collector I is sucked back by the blower G through the 75 pipes J, J', J² and J³, a complete circulation being thus obtained. If this complete circulation were not maintained, the current would produce a pressure in the collector and in the cooling chamber, and cause a loss of 80 sulfur or vapors if any opening or crevice were to allow said current to escape. Further, the pressure would finally become so great that the apparatus would have to be stopped to prevent explosion.

If the subliming plant is only small, with 85 one retort, a cooling tube may be used to convey the sulfur into the collector, instead of the cooling chamber. If an increased draft or current is desired, the injector K 90 shown in Fig. 3 may be used.

Up to the present time, sublimed sulfur, 95 could not be manufactured in a continuous way, as the large chambers heretofore used, in which the sulfur was condensed, gave sulfur of various degrees of fineness, according to the length of said chambers and distance from the retort, thus resulting in an uneven product. It was also necessary to allow these chambers to cool from one to two days, or 100 until the residue of condensed sulfur had deposited itself on the ground, before the said chambers could be entered with safety for the purpose of collecting the manufactured sulfur. Thus a great deal of time was lost 105 and the constant change from heat to cold caused great wear and tear on the iron retorts. Further the sulfur prepared by the old processes had to be mixed and selected before it is ready for the market. Another 110 great loss or waste in the old process is due to the fact that more than 40% of the sublimed

sulfur melts during the process in the sublimation chambers near the retort, instead of being transformed into powder.

To avoid the melting of the sulfur and its formation into groups of particles my apparatus causes a movement of the vapors and of the particles of sulfur, also a quick circulation of the inert gas (which is used instead of air, so as to prevent the danger of explosion) which gas is sucked into the retort by the fan and drawn from the retort and forced into the cooling chamber, and from the cooling chamber into the collector. This procedure has another advantage, as the strong current sucks the vapors of sulfur coming from the retort and tends to produce a vacuum, by which sulfur is distilled much more rapidly and with less heat, the charge in the retort is evaporated in much less time, thus resulting in considerable saving in fuel and labor. With my apparatus the same cooling chamber enlarged would serve for several retorts, placed one near to the other. The same fan and the same collector will also suffice for two or four retorts; meanwhile, if working with only one retort, no chamber is required, a tube or a conveying case with parallel metal sides being sufficient to hasten the cooling of the vapors. As before stated, the sulfur, before being introduced into the retort, is melted in the ordinary way in the boiler E. Although a strong current of air would undoubtedly cool the vapors, so that no fire could break out, still I prefer to use the inert gas as electric phenomena must occur while sulfur is moving in air in the form of a very fine powder, which phenomena might cause accident. The inert gas which is employed is produced with very small cost and makes an outbreak of fire or an explosion absolutely impossible.

Before starting the apparatus it is to be filled entirely with inert gas, using the same blower fan for the purpose, the air in the apparatus being permitted to escape through a suitable valve as d.

Various modifications may be made without departing from the nature of my invention.

The inert gas is sucked into the apparatus through the tube X at the start, and may be admitted continuously during the process.

The method herein described forms the subject matter of another application for patent filed by me February 6, 1905, Serial No. 299,418.

I claim:

1. The apparatus for subliming sulfur, consisting of the retort A, communicating with boiler E, and with the blowing pipes F, F', and F'', cooling chamber H, collector I and suction pipes J, a blower G being placed between the pipes J and F', all arranged to form a closed circulating system, as specified. 60

2. The combination of the cooling chamber H and means for forcing inert gases and powdered sulfur into it, with its discharge pipe H' having downward outlet a, and with the collector I and means for withdrawing gas therefrom, all for depositing sulfur on the 70 bottom of the collector.

3. An apparatus for subliming sulfur, which comprises a boiler, a retort communicating therewith, an injector having a suction connection with the retort, a cooling chamber having a connection with the outlet of the injector, a collector connected with the outlet of the cooling chamber, and means for conveying the gases from the collector to the injector so as to form a continuous circuit. 80

4. An apparatus for subliming sulfur, which comprises a retort having an inlet connection and an outlet connection, a boiler connected with the inlet connection of the retort, a suction pipe communicating with the outlet connection of the retort to withdraw vapors therefrom, a collector for the gas and vapors from said retort and suction pipe, and means for conveying the gases from the collector back to the suction pipe so as to 90 form a continuous circuit.

In testimony whereof I have signed my name in the presence of two subscribing witnesses.

ARTHUR WALTER.
